(57) **CLAIM**

The ornamental design for a door for a vehicle, as shown and described.

DESCRIPTION

This application contains subject matter related to the following co-pending U.S. design patent applications:

Application Ser. No. 29/530,457, filed Jun. 17, 2015 and entitled “Front Door for a Vehicle”;

Application Ser. No. 29/594,683, filed herewith and entitled “Vehicle, Toy, and/or Replicas Thereof”; and

Application Ser. No. 29/594,689, filed herewith and entitled “Door for a Vehicle”.

FIG. 1 is a front view of a door for a vehicle according to the design;

FIG. 2 is a left perspective view thereof;

FIG. 3 is a right perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

1 Claim, 8 Drawing Sheets
